UNITED STATES PATENT OFFICE.

CHARLES HEWITT AND JAMES WITHERINGTON, OF CHAMBERSBURG, AS-
SIGNORS TO THE TRENTON IRON COMPANY, OF TRENTON, N. J.

MACHINE FOR COILING WIRE AND RODS.

SPECIFICATION forming part of Letters Patent No. 285,359, dated December 14, 1880.

Application filed March 21, 1879.

To all whom it may concern:

Be it known that we, CHARLES HEWITT and JAMES WITHERINGTON, both of Chambersburg, New Jersey, have invented an Improvement 5 in Machines for Coiling Wire Rods and the like, of which the following is a full, clear, and exact description, reference being had to the accompanying drawings, forming part hereof, in which—

10 Figure 1 is a side elevation, partly in section, of a machine embodying our invention; Fig. 2, an end elevation of the same looking toward the face-plate of the reel; Fig. 3, a view, in perspective, of the wire guide-posts, 15 showing the relative position of the posts and reel-pins; Fig. 4, a side sectional elevation of the reel, showing the position of the reel-pins when collapsed for the removal of the coil; and Fig. 5, a side elevational detail of a modified construction of reel, in which the pins are angled off toward the circumference of the face-plate, so as to prevent any possibility of the coil from flying off the pins during process of reeling.

25 Similar letters of reference indicate corresponding parts in all the figures.

Our invention relates to the construction and operation of machinery for coiling wire, wire rods, and like articles; and it consists in 30 the devices and combinations thereof herein-after described and claimed.

The object of the invention is the production of an apparatus for reeling coils of wire and the like, in which attachment of the wire to be reeled is readily and surely made while 35 the reel is revolving, and without its stoppage, upon which the coil is held without possibility of flying or falling off during the reeling action, and from which the finished coils 40 are easily removed.

Referring to the drawings, the following is a description of a machine embodying our invention: A is a frame-work, of any suitable construction, in which is journaled a shaft, B, 45 revolved at any desired speed, by means of one or more driving-pulleys, b, or otherwise actuated to rotation by any convenient device or arrangement of steam-gearing.

At one extremity of the shaft B is secured a

face-plate, C, having a series of projecting 50 reel-pins, c, arranged in a circle or other suitable relation thereon to form a reel for coiling wire.

Secured to or forming a part of the face-plate centrally is a projection, c', pulley, or other 55 equivalent device, extending or not beyond the coil-pins. The object of this projection is to form a stop against which the free end of the fresh wire will catch as the same is thrown, projected, or otherwise entered 60 against the face-plate within the circle of reel-pins, and through the medium of which stopping action the end of the wire is bent around a reel-pin as the reel rotates, so as to be hooked to the pin, all substantially in 65 the manner illustrated in Fig. 2 of the drawings, in which figure is represented, in dotted lines u, a side view of the wire when first thrown into the reel, while at w is represented the wire as it appears hooked around a pin 70 through the action of the stop as the reel rotates, attachment being effected by the combined action of the projection and pin in the revolution of the reel, the central projection serving as a stop, by the aid of which the 75 end of the fresh wire is caught by and bent around a reel-pin.

The reel-pins c are pivoted at z to the face-plate, and terminate in heels v, projecting out beyond and at the back side of the face-plate, 80 through which the pins pass; and these heels are embraced within and operated by a disk-cam, X, journaled upon the shaft B, rotating therewith, and playing horizontally thereupon, as hereinafter set forth. The reel-pins may, 85 however, be pivoted in any suitable manner other than that described.

Connection is made between the heels of the coil-pins and the cam-disk or pin-operating device by a flaring slot or a series of flaring slots, 90 x, or their equivalent, in the cam-disk, into which slot or slots the heels of the pins enter, and which slots are adapted to deflect said pins to either side of the perpendicular as the disk is moved on the shaft, as hereinafter set 95 forth and as shown in the drawings.

As a convenient means of moving the cam-disk or other pin-operating device along the

shaft we have devised the following arrangement: S is a treadle pivoted in the frame-work, a toe, s, of which bears against a lever, T, also pivoted to the frame-work, the upper extremity 5 of which lever is connected with the hub y of the cam-disk in such manner that the hub is free to rotate at all times, although deflection of the lever T will slide the hub and disk backward and forward along the shaft.

10 K is a spiral spring surrounding the shaft between the hub of the cam-disk and a collar on the shaft or a part of the frame-work, substantially in the manner represented in Fig. 1, and in such manner as to keep the cam-disk 15 constantly pressed over toward the face-plate in the position indicated in Fig. 1, in which position the heels of the reel-pins are embedded within the slots x of the disk-cam, so that the pins stand off at right angles to the face-plate.

In Fig. 5 the disk is pressed over against the face-plate to such extent that the reel-pins are angled out or away from a common center, so as to form a flaring coil-bearing circumference inclined back toward the face-plate, so that a coil tends to slide back against the face-plate and cannot fly off or fall from the pins.

The reel-pins can be kept at any desired inclination with reference to the face-plate, 25 the simple adjustment of the heels of the pins and slots in the disk-cam, no special mechanism—such as the cam-disk—being alone capable of accomplishing such result, but any mechanism adapted to tilt the pins with respect to 30 the plane of the face-plate being suitable for the purpose.

When the treadle S is depressed through the medium of the lever T it slides the cam-disk backward on the shaft and away from the 40 face-plate, in so doing compressing the spring K, and by the action of the slots on the heels of the reel-pins deflecting the latter from their former position inwardly—in other words, converging or collapsing them toward a common 45 center—so that a coil upon them falls off, the upper pins presenting a downwardly inclined or deflecting surface, off which the coil drops by gravity, or from which the coil is readily removed by reason of the diminished coiling circumference of the series of reel-pins.

G is a friction-pulley secured to the shaft B, so as to rotate with it. G' is a friction brake-band semi-encircling said pulley, and extending down to a treadle, H, to which it is connected, whereby, by pressure upon the treadle 55 the shaft is brought to a stop.

The guide-posts F and F' are, near their upper ends, provided with flaring slots or guides f f', provided with retaining-ribs g g', by the 60 joint action of which the wire is caught and retained as the operator throws the wire over and between the posts. The guideways are set upon opposite sides of their respective posts, in the manner represented, while the 65 posts also are set out of line, whereby the

wire is forced into close contact with the inner side of each guideway and retained within the same without possibility of escape.

In the use of our machine the operator, 70 grasping the wire as it emerges from the rolls, carries it to the reel, and, throwing it over and between the posts, by the guideways and ribs of which it is caught and retained, throws it into the reel below the projection and among the pins, attachment being effected while the reel is in motion by the combined action of the projection and reel-pins, as hereinbefore set forth.

It is well understood by those skilled in the art of metal-reeling that rods and the heavier 80 wires cannot be reeled with good practical results except upon a face-plate or disk-reel, as opposed to an arm-reel, for reasons connected with the entering and attachment of the wire.

Such being a convenient construction of machine for carrying out our invention, the essence thereof consists, first, in so combining a series of reel-pins with a face-plate or its equivalent that the reel-pins can be converged in order to lessen their coil-bearing circumference for the removal of the coil; second, in combining with a face-plate provided with a series of coil-pins a central projection, or a projection located within the series of pins, to form a stop which the end of the fresh wire encounters, and which aids in bending the same around the pins for the attachment of the wire to the reel; third, in combining with a face-plate a series of reel-pins adapted 90 to be held at right angles to the plane of said plate, or to be held in a position divergent from a common center, for the winding of the coil, as well as adapted to be converged toward a common center for the removal of the 95 coil; and further consists in arrangements of devices for the accomplishment of the same.

Having thus described our invention, we claim—

1. In a machine for coiling wire, rods, &c., 110 the combination, with a rotating disk or face-plate provided with a central projection or stop, of a series of coil-pins projecting from the disk and encircling the stop, for the purpose specified.

2. In a machine for coiling wire, rods, &c., 115 the combination of a rotating disk or face-plate provided with a central projection or stop, a series of coil-pins encircling the stop, projecting from and pivoted to the disk, and mechanism for simultaneously converging the coil-pins, for the purpose specified.

3. In combination with a face-plate, C, provided with the coil-pins c, the cam-disk X, connected with said pins and adapted to control the movement of the same when actuated by suitable mechanism, such as the treadle S and lever T, substantially as shown and described.

4. The combination, in an apparatus for reel- 130

ing wire, of a rotating disk carrying an annular series of coil-pins with a projection or pin arranged within the circle of said series, and a guide located without said series, substantially as described.

5. In a machine for coiling rods, &c., the guide-posts F and F', jointly provided with guideways constructed and arranged, in combination with the reel, as shown and described.

10. 6. The combination, with a rotating disk, C, provided with a central stop, of a series of pivoted coil-pins, e, adapted by construction

to be held in suitable position to receive the coil, and also adapted to be converged for the removal of the coil, substantially as described. 5

In testimony whereof we have hereunto signed our names this 18th day of March, A. D. 1879.

CHAS. HEWITT.
JAMES WITHINGTON.

In presence of—

J. BONSALL TAYLOR,
THEO. C. MAPLE.
